MINIATURE TROLLEY CAR OR SIMILAR ARTICLE

Frederick H. Bultman, Lakewood, Ohio

Application January 19, 1955, Serial No. 34,069

Term of patent 14 years

(Cl. D34—15)

Fig. 1

Fig. 3

Fig. 1 is a side elevational view of a miniature trolley car or similar article, showing my new design;

Fig. 2 is an end elevational view thereof, the opposite end having substantially the same appearance; and

Fig. 3 is a cross-sectional view thereof, taken on line 3—3 of Fig. 2.

I claim:

The ornamental design for a miniature trolley car or similar article, as shown and described.
